UNITED STATES PATENT OFFICE.

EARL W. LESHER, OF CLEVELAND, OHIO, ASSIGNOR TO THE MECHANICAL PRODUCTS COMPANY, OF CLEVELAND, OHIO, A CORPORATION OF OHIO.

ROBE-RAIL LOCK.

1,162,086.

Specification of Letters Patent. Patented Nov. 30, 1915.

Application filed May 21, 1915. Serial No. 29,530.

To all whom it may concern:

Be it known that I, EARL W. LESHER, a citizen of the United States, and a resident of Cleveland, county of Cuyahoga, and State of Ohio, have invented a new and useful Improvement in Robe-Rail Locks, of which the following is a specification, the principle of the invention being herein explained and the best mode in which I have contemplated applying that principle, so as to distinguish it from other inventions.

The subject of the present invention is a device adapted for use in locking robes, blankets and articles of clothing to a rail, and will be of particular use in automobiles which generally have a rail extending across the back of the front seats upon which may be hung coats, robes, etc. No effective means for locking these robes and coats to the rail have yet been provided and the present device is intended to provide a simple but effective mechanism for this purpose.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—Figure 1 is a view in perspective showing the back of a front seat in a vehicle provided with a rail to which a robe is clamped by my device; Fig. 2 is a bottom view of the device when closed; Fig. 3 is a transverse section of the device, the plane of the section being indicated by the line 3—3 in Fig. 4; Fig. 4 is a longitudinal section on the line 4—4 in Fig. 3; Fig. 5 is a view of a detail of construction; and Figs. 6 and 7 are partial end views of the device with the flanges on the jaws removed to show features of the construction.

The device comprises two suitably connected jaws 1 and 2, which are preferably pivoted together and are constructed in the manner illustrated and which are provided with curved engaging sides or edges 3 which will be scalloped or waved as illustrated in Fig. 2 for the purpose of holding a robe therebetween against lateral displacement. It is highly desirable that the two pivotally

connected jaws be capable of being locked in any desired relation, as the robes and coats which will be held will be of varying thickness, and if there are only a certain specified number of positions, then in some instances the robe will not be held securely, since the jaws cannot be spaced an exact distance apart equal to the thickness of the robe. Accordingly I have provided means for locking the jaws in any desired relation, and it is only necessary to place the device over the robe as illustrated in Fig. 1, move the jaws together until they securely engage and "bite" or grip the article which is being held. The locking mechanism thereafter maintains the jaws in this relation until the device is unlocked, when the jaws may be spaced apart and the device removed.

Attached to one of the jaws is a resilient shoe 4, best shown in Fig. 5, which is mounted at an angle to the plane of the side of such jaw upon a suitable screw or stud 5, and is normally maintained in such position by means of a strong spring 6 disposed between the side of the jaw and the shoe. Upon the other of the two jaws there is mounted an arcuate rod 7, all points of which are equidistant from the pivotal axis of the two jaws, such rod extending through an aperture 8 formed in the shoe 4 and being provided with a head 9 which prevents the rod from being withdrawn from such aperture. The aperture 8 is formed in the shoe 4 in such position that this shoe when pressed in the direction given it by the spring 6 will cause the edges of the shoe about the aperture to frictionally engage and grip into the sides of the rod, thus maintaining the rod against movement away from the shoe. If the rod is pulled away from the shoe the friction between the rod and shoe will cause the latter to be pulled even farther away from the side of the jaw to which it is attached, thus causing the sides of the shoe about the aperture 8 to grip the rod even more firmly. If the rod is moved in the other direction, that is toward the shoe, the friction between the shoe and rod will move the shoe inward, thus releasing the grip of the shoe on the rod. As soon as movement ceases the shoe will be returned into a frictional engagement with the rod by means of the spring 6.

The rod and the shoe are mounted between the two jaws, as indicated, and are

normally covered by means of a plate 10 which is attached to the jaw 1 and is provided with a flange 11 parallel with the side of the jaw 2 when the latter is in the closed 5 position of the device. In this way the mechanism is securely closed against being tampered with, and is additionally covered by means of the broad flanges 12 formed on each jaw.

10. It will be seen that the device is automatically operative to lock against opening in any desired position, although the jaws can still be moved closer together, as such action releases the engagement between the shoe 15 and the rod. In order to permit opening of the jaws for removal of the device from whatever it is attached to, and to still make this removal impossible for any one but the lawful owner, locking mechanism is provided which can be actuated from outside of the device, and it will be obvious that this locking mechanism can be actuated either by a key or by the combination means which are here illustrated. It is only necessary, in 25 order to release the frictional engagement between the shoe and the rod, to move the shoe toward the jaw to which it is attached, and this can be done by displacing this shoe by means of a plunger 13 reciprocably 30 mounted in the device between the jaws and normally maintained out of contact with the shoe by means of the spring 14. This plunger is provided externally of the jaws with a knob or handle 15 which may be used 35 by the operator to depress the rod and unlock the jaws.

In the present construction I have employed this plunger as a part of a combination lock, the knob 15 being provided with 40 numbers arranged at intervals around its periphery and adapted to serve in the same way that the numbers usually serve in the dial of a combination lock. Fixed between the jaws and encircling the plunger is a disk 45 or stationary tumbler 16 provided with a slot 17 adjacent to the plunger. Disposed in contact with this stationary tumbler 17 is a second rotatable tumbler 18 which is provided with a plurality of notches 19 of equal 50 length, and a long notch or slot 20, such long slot 20 being of the same length and width as the slot 17 in the tumbler 16. Attached to the disk 18 is a lug or shoulder 21 which is adapted to be engaged by a pin 22 attached to the plunger.

In order to operate the combination and release the device, the plunger 13 is first rotated until the pin 22 engages the lug 21. It is then again rotated until the long slot 20 60 on the tumbler 18 registers with the slot 17 in the stationary disk 16. The plunger is then depressed, the pin or lug 22 passing through the registering slots 17 and 20, thus permitting the plunger to be depressed to 65 such a distance that the end contacts the

curved end of the shoe 4, thus displacing the same with respect to the rod and releasing the frictional grip thereon. The jaws of the device may then be moved apart and the device removed from whatever article it was 70 attached to.

In order to operate the combination lock the tumblers are initially positioned and set so that rotation of the plunger a given distance in different directions will bring the 75 slots 17 and 20 into register. Movement of the plunger can be secured by the employment of the numbered divisions 25 on the circumference of the knob 15 in connection with the starting point on the jaws indicated 80 by the projection 26. In this particular the permutation lock is similar to others in general use and will be readily understood.

My device will be seen to be automatically locking against spreading although permitting further closing movement. Furthermore, the jaws are thus automatically locked at any desired point, affording a multitude of adjustments and giving a secure grip on any article irrespective of its thickness. 85

Other modes of applying the principle of my invention may be employed instead of the one explained, change being made as regards the mechanism herein disclosed, provided the means stated by any of the following claims or the equivalent of such stated means be employed. 90

I therefore particularly point out and distinctly claim as my invention:—

1. A device of the class described comprising pivotally mounted jaws, and members attached to said jaws and normally frictionally gripping each other to prevent movement of said jaws away from each other, said members having a sliding frictional engagement. 100

2. A device of the class described comprising pivotally mounted jaws, an arcuate rod attached to one of said jaws and disposed concentrically about the axis of said 110 jaws, and a resilient plate attached to the other of said jaws and normally resiliently engaging said rod to prevent movement of said jaws apart.

3. A device of the class described comprising pivotally mounted jaws, a curved apertured plate attached to one of said members, an arcuate rod attached to the other concentrically about its axis, said rod extending through the aperture in said plate 115 and being resiliently gripped thereby, and means for moving said plate into a disengaging position.

4. A device of the class described comprising pivotally connected jaws, an apertured resilient member attached to one of said jaws, a second member attached to the other of said jaws and extending through the aperture in said resilient member, the latter being normally at an angle to said second 125 130

member adapting it to frictionally grip the same, and locking mechanism adapted to displace said resilient member, thereby disengaging the same from said second member.

5. A device of the class described comprising pivotally connected jaws, a shoe attached to one of said jaws and having an aperture therein, a rod attached to the other of said jaws and extending through such aperture in said shoe, said shoe being positioned and constructed to normally grip said rod to prevent movement of said jaws apart, and a member movably mounted on one of said jaws and adapted when moved to displace said shoe from its rod engaging position thereby permitting movement of said jaws away from, as well as toward, each other.

20 6. A device of the class described comprising pivotally connected jaws, a shoe attached to one of said jaws, and having an aperture therein, a rod attached to the other of said jaws and extending through such aperture in said shoe, said shoe being positioned and constructed to normally grip said rod to prevent movement of said jaw apart, and a plunger reciprocably mounted in said device and adapted when actuated in one direction to contact and displace said shoe from its rod engaging position.

30 7. A device of the class described comprising pivotally connected jaws, frictional means for locking said jaws against opening, a plunger adapted to release said frictional means from engagement with said jaws, and permutation lock mechanism for controlling the movement of said plunger.

40 8. A device of the class described, comprising pivotally connected jaws, a shoe pivotally attached to one of said jaws and having an aperture therein, a rod attached to the other of said jaws and extending through such aperture in said shoe, means normally forcing said shoe into frictional engagement with said rod thereby preventing movement of said jaws apart.

50 9. A device of the class described comprising pivotally connected jaws, a shoe pivotally attached to one of said jaws and having an aperture therein, a rod attached to the other of said jaws and extending through such aperture in said shoe, resilient means normally forcing said shoe into frictional engagement with said rod, thereby preventing movement of said jaws apart.

60 10. A device of the class described comprising pivotally connected jaws, a shoe attached to one of said jaws, and having an aperture therein, a rod attached to the other of said jaws and extending through such aperture in said shoe, resilient means normally forcing said shoe into frictional engagement with said rod thereby preventing movement of said jaws apart, and a mem-

ber movably mounted on one of said jaws and adapted when moved to displace said shoe from its rod engaging position.

11. A device of the class described comprising pivotally connected jaws, a shoe attached to one of said jaws, and having an aperture therein, a rod attached to the other of said jaws and extending through such aperture in said shoe, resilient means normally forcing said shoe into frictional engagement with said rod thereby preventing movement of said jaws apart, and a plunger reciprocably mounted on said device and adapted when actuated in one direction to contact and displace said shoe from its rod engaging position.

70 12. A device of the class described comprising pivotally connected jaws, a shoe attached to one of said jaws, and having an aperture therein, a rod attached to the other of said jaws and extending through such aperture in said shoe, resilient means normally forcing said shoe into frictional engagement with said rod thereby preventing movement of said jaws apart, a plunger reciprocably mounted on said device and adapted when actuated in one direction to contact and displace said shoe from its rod engaging position, and means adapted to lock said plunger against such actuation.

80 13. A device of the class described comprising pivotally connected jaws, a shoe attached to one of said jaws, and having an aperture therein, a rod attached to the other of said jaws and extending through such aperture in said shoe, resilient means normally forcing said shoe into frictional engagement with said rod thereby preventing movement of said jaws apart, a plunger reciprocably mounted on said device and adapted when actuated in one direction to contact and displace said shoe from its rod engaging position, means adapted to lock said plunger against such actuation, and combination locking means adapted to lock said plunger against such actuation.

90 14. A device of the class described comprising pivotally connected jaws, a shoe attached to one of said jaws, and having an aperture therein, a rod attached to the other of said jaws and extending through such aperture in said shoe, resilient means normally forcing said shoe into frictional engagement with said rod thereby preventing movement of said jaws apart, and locking mechanism adapted to displace said shoe from its rod engaging position.

100 15. A device of the class described comprising pivotally connected jaws, a shoe attached to one of said jaws, and having an aperture therein, a rod attached to the other of said jaws and extending through such aperture in said shoe, resilient means normally forcing said shoe into frictional engagement with said rod thereby preventing

- movement of said jaws apart, and combination locking mechanism adapted to displace said shoe from its rod engaging position.
5. 16. A device of the class described comprising pivotally connected jaws, a shoe attached to one of said jaws, and having an aperture therein, a rod attached to the other of said jaws and extending through such 10 aperture in said shoe, resilient means normally forcing said shoe into frictional engagement with said rod thereby preventing movement of said jaws apart, and combination locking mechanism including a plunger adapted, upon actuation of said mechanism, to displace said shoe from its rod engaging position.

Signed by me, this 12th day of May 1915.

EARL W. LESHER.
